FOLDING BED

Göte Y. M. Göpertz, Jonkoping, Sweden

Application October 25, 1950, Serial No. 192,023

6 Claims. (Cl. 5—8)

1

The present invention relates to a folding bed, such as a chair or a sofa, with a bed frame composed of a number of sections hingedly connected to each other. Folding beds of this kind are usually made of wood, and the use of this material results in large dimensions of the piece of furniture. Metal constructions have also been used to some extent, but these constructions have been complicated.

An object of the invention is to provide a folding bed of a simple construction comprising a few number of parts.

Another object is to reduce the dimensions of the main frame within which the folding bed frame is located.

A further object is to obtain a folding bed which can be easily disassembled for transport and storing and which is of a low weight.

With these and other objects in view a folding bed according to one form of the invention will be hereinafter described, reference being made to the accompanying drawing in which:

Figure 1 is an inside elevation of an end portion.

Figure 2 is a top view of a sofa with end portions according to Figure 1 and only one of the two bed frames shown in part in the drawing.

Figure 3 is a front view of and Figure 4 a side elevation of the back portion.

Figure 5 is a section according to line V—V in Figure 4.

Figure 6 is a section along line VI—VI in Figure 3, and

Figure 7 is a side elevation of an intermediate support.

Figure 8 is a section along line VIII—VIII in Figure 2 of the sofa as folded.

The end portion as shown in Figure 1 is formed by bending a single tube of steel or other metal and comprises an upper frame member 1, a fore frame member 2, a lower frame member 3 and two substantially vertical frame members 4, 5 of which the member 4 is located behind the member 5 and connected with this member 5 by a short frame member 6 at their upper ends. The members 1 and 3 are substantially horizontal and parallel. The frame member 1 is welded to the frame member 5, and the lower end of the member 5 is welded to the frame member 3. This end portion is preferably made substantially plane, and owing to its special construction it has been found to be very rigid. The end portion is supported by a foot 7 and another foot 8 provided with a roller.

These feet are preferably welded to the frame 55 the frame members 32. The section 31 is

2

member 3. This member 3 passes over along a continuous curve into the frame member 4, and the foot 8 is, therefore, located within the extension of frame member 4. The back portion is composed of an upper frame member 9 of a metal tube, the ends of which are bent so as to form two vertical frame members 10, 11. The lower ends thereof are welded to a metal tube 12, the ends of which are closed by a metal plug 14 having a threaded aperture 13. A middle cross frame member 15 of a metal tube is welded at the ends to the frame members 9 and 12 and a number of similar cross members 16 of a less diameter and preferably also of metal tubes are fastened by welding in a similar manner. The lower portions of all cross members are bent forwards along a curve corresponding to that between the frame members 3 and 4 in the end portions. For connecting the back portion with the end portions it is provided at each end with two-headed pins 17, which can be introduced in and lowered in corresponding perforations 18 in the frame member 4.

A perforation 19 in frame member 3 is located 25 opposite to the threaded perforation 13, in which a bolt passing through the aperture 19 is screwed and tightened. The three connection points will thus be located so as to form a triangle, whereby the connection between the back portion and the end portions becomes very rigid.

The intermediate support 42 is formed by bending a metal tube to a closed and plane construction and comprises an upper frame member 20, a fore frame member 21, a lower frame member 22 and a rear frame member 23. A single foot 24 is welded to the fore end of frame member 22. For connection of the intermediate support with the back portion it is provided with two headed pins 25 to be introduced into and lowered in corresponding perforations 26 in the middle 30 cross frame member 15. The frame member 23 is further provided with an aperture 27 opposite to a corresponding aperture 28 in the frame member 12 and by means of a bolt, both portions can be screwed and drawn together. Also in this case the three connection points form a triangle.

Each one of the bed frames comprises a rear or lower U-shaped section 28 formed of a metal tube with an end frame member 29 and two longitudinal frame members 30. These latter are hingedly connected with an intermediate section 31, comprising two longitudinal frame members 32 and two cross members 33 located at a lower plan and having upwardly bent ends welded to 35 the frame members 32. The section 31 is

hingedly connected with a seat section 34, which is connected in a similar manner with a back section 49 resting on and entirely supported by the upper frame member 9 of the back portion. The back section is provided with two bows 50 bearing against the front side of the frame member 9 and has two portable legs 51 for supporting the back section of the bed frame in unfolded position. A closed metal frame 52 is removably fastened to the longitudinal frame members 34 of the seat section and is at the rear end bent upwards so as to form a bow. To this bow a lower back cushion 53 may be fastened, and the horizontal portion may carry an upholstery indicated at 54. A removable frame 55 rests on the upper end of frame 52 and carries an upper back cushion 56. At least all the peripheral frame members are made of metal tubes.

Each of the frame members 32 is provided with headed pins 35 introduced in corresponding perforations 36 in the end portion and 37 in the intermediate support whereby the bed frame is pivoted in the main frame of the sofa. Flanges 38 with apertures 39 are welded to the inside of the longitudinal frame members for fastening a resilient bed bottom of any suitable type.

When the bed frame is turned to its unfolded position as shown in Figure 2, the end frame member 29 rests on the upper portion of two guide members 40 welded each to a cross member 16 and to the lower frame member 12 of the back portion. The lower portion of the guide members 40 is bent to a hook 41, and when the bed frame is being folded together the frame member 29 slides on the guide members 40 unto a lower end position, where it is retained by the hook 41.

For further supporting of the end section 28 in unfolded position of the bed frame the upper frame member 20 of the intermediate support is provided with a bolt 43 passing through the frame member 20 and having a handle at its upper end, whereas its lower end is provided with a cross bar which after turning 90° from the position shown in Figure 7 supports from below the frame member 30 of the end section. For supporting the outer frame member 30 a vertical pivot 45 passing through the member 30 has its upper portion 46 bent at a right angle so as to rest in its locking position against the upper frame member 1. Secured to the portion 46 is a plate spring 47 extending above and along the frame member 1. When the bed frame is to be folded the pivot 45 is turned by means of the spring 47 an angle of 90°, whereby the section is released from the frame member 1 and the spring 47 will extend over the bed in order to keep the same in its position, when the bed together with the bed frame is folded together.

It is obvious that the invention as well can be applied to a chair having only one bed frame. In this case the intermediate support 42 is removed and the back portion is shortened to half of its length. Also other modifications may be possible without departing from the scope of the invention.

I claim:

1. In a folding bed, a main frame comprising two end members and a back member connected thereto, and a bed frame, each one of said end members being disconnectably attached to said back member and each comprising two substantially horizontal metal frame portions arranged one above the other and a substantially vertical rear metal frame portion, said back member

comprising a substantially rectangular metal tube frame with a plurality of substantially vertical cross bars and having its lower portion including the lower portions of the cross bars bent continuously forwards, at least one of said cross bars carrying a sloping guide member, and said bed frame comprising a plurality of movable sections hingedly connected one to another and having their peripheral frame portions formed of metal tubes, one of said sections being pivotally supported by said main frame, and one end section resting with its free end on said guide member.

2. In a folding bed, a main frame comprising two end members and a back member connected thereto, and a bed frame, each one of said end members being disconnectably attached to said back member and each comprising two substantially horizontal metal frame portions arranged one above the other and a substantially vertical rear metal frame portion, said back member comprising a substantially rectangular metal tube frame with two substantially vertical end frame portions connected each to one of said rear frame portions and with a plurality of substantially vertical cross bars, at least one of said cross bars carrying a sloping guide member, and said bed frame comprising a plurality of movable sections hingedly connected one to another and having their peripheral frame portions formed of metal tubes, one of said sections being pivotally supported by said main frame, and one end section resting in the bed position with its free end on the top of said guide member and with its frame portions at a short distance from the adjacent section on two locking devices mounted swingably about vertical axis, at least one of them being carried by one of said end members and mounted on the upper one of its both horizontal metal frame portions.

3. In a folding bed, a main frame comprising two end members and a back member connected thereto, and a bed frame, each one of said end members comprising two substantially horizontal metal tube frame portions arranged one above the other and two substantially vertical tube frame portions arranged one behind the other and connected to each other at their upper ends, said back member comprising a substantially rectangular metal tube frame with a plurality of vertical cross bars, at least one of which carries a sloping guide member, and said bed frame comprising a plurality of movable sections hingedly connected one to another and having their peripheral frame portions formed of metal tubes, one of said sections being pivotally supported by said main frame and one end section resting with its free end on said guide member.

4. A folding bed as claimed in claim 3, and in which the lower portions of the rear vertical frame portions of the end members and of the vertical frame portions and cross bars of the back member are bent forward along a continuous curve, and that each one of said vertical frame portions of the back member and the rear vertical frame portion of the adjacent end member are detachably connected at three points forming a triangle.

5. In a folding bed, a main frame comprising two end members and a back member connected thereto, two bed frames, and a transverse vertical frame located between and supporting said bed frames, each one of said end members comprising two substantially horizontal metal frame portions arranged one above the other and a

substantially vertical rear metal frame portion, said back member comprising a closed metal tube frame with two horizontal frame portions and two substantially vertical frame portions discon-
nectably attached to one of said vertical rear
metal frame portions, and with a plurality of
cross bars extending between said both horizontal
frame portions, at least one of said cross bars
carrying a sloping guide member, said trans-
verse frame being formed as a closed metal tube
frame, detachably connected with one of said
cross bars of the back member, and each one
of said frame members comprising a plurality
of movable sections hingedly connected one to
another and having their peripheral frame por-
tions formed of metal tubes, one of said sections
being pivotally supported by one end member
and said transverse frame, and one end section
resting with its free end edge on said guide
member.

substantially vertical rear metal frame portion, said back member comprising a closed metal tube frame with two horizontal frame portions and two substantially vertical frame portions discon-
nectably attached to one of said vertical rear
metal frame portions, and with a plurality of
cross bars extending between said both horizontal
frame portions, at least one of said cross bars
carrying a sloping guide member, said trans-
verse frame being formed as a closed metal tube
frame, detachably connected with one of said
cross bars of the back member, and each one
of said frame members comprising a plurality
of movable sections hingedly connected one to
another and having their peripheral frame por-
tions formed of metal tubes, one of said sections
being pivotally supported by one end member
and said transverse frame, and one end section
resting with its free end edge on said guide
member.

6. A folding bed as claimed in claim 5, and in
which an upper frame portion of the transverse
frame is provided with a vertically pivoted rod
having at its lower end a cross bar serving as a
locking member for the bed frame in unfolded
position.
